UNITED STATES PATENT OFFICE.

EMMA K. MUNCH, OF EMPORIA, KANSAS.

SANITARY STOOL-SLIP.

1,159,070.

Specification of Letters Patent. Patented Nov. 2, 1915.

Application filed October 13, 1914. Serial No. 866,499.

To all whom it may concern:

Be it known that I, EMMA K. MUNCH, a citizen of the United States of America, residing at Emporia, in the county of Lyon 5 and State of Kansas, have invented certain new and useful Improvements in Sanitary Stool-Slips, of which the following is a specification, reference being had therein to the accompanying drawing.

10 This invention relates to a sanitary stool slip and has for its object the production of a simple and efficient slip which may be easily and readily attached to the seat of the stool.

15 Another object of this invention is the production of a simple and efficient stool slip which will fit snugly around the edge and over the upper face of the seat of the stool to constitute a sanitary protector 20 therefor.

25 With these and other objects in view this invention consists of certain novel combinations, constructions, and arrangements of parts as will be hereinafter fully described and claimed.

In the accompanying drawing:—Figure 1 is a longitudinal section through the seat of the stool showing the protector applied thereto. Fig. 2 is a rear elevation of the 30 seat of the stool showing the protector applied thereto. Fig. 3 is a bottom plan view of the sanitary protector. Fig. 4 is a perspective view of the protector. Fig. 5 is a transverse sectional view through the 35 protector showing the same applied to the seat of a stool.

40 By referring to the drawing it will be seen that 1 designates the seat of the stool which is mounted and supported in the usual manner, and the protector 2 is adapted to fit over the seat and constitute an efficient covering therefor. The protector 2 comprises an upper strip 3 and an under segmental strip 4, the upper strip 3 being 45 connected around its forward and side edges to the forward and side edges of the under strip 4 by having the edges joined together and bound by means of a binding tape 5 as clearly illustrated in Figs. 1 and 5. It 50 should be understood that this binding tape 5 is stitched through the adjoining edges of the upper strip 3 and the lower strip 4. The upper strip 3 is provided with a centrally located aperture 6 which is provided 55 with a reinforcing or binding tape 7 substantially U-shaped in cross-section stitched

around the edge thereof to constitute a protector and reinforcement therefor. The inner edge of the under strip 4 is also reinforced by means of a binding tape 8 which 60 is also substantially U-shaped in cross-section and is stitched to the inner edge of the under strip 4, and this tape also constitutes an efficient reinforcement for the protector or edge of the under strip 4. It 65 should be understood that the under strip and top strip 3 will constitute a pocket for fitting over the forward end of the seat 1 as is illustrated clearly in Fig. 1.

70 It should be understood as is clearly illustrated in Fig. 3 that the under strip 4 is provided with straight side edges 9 which are so constructed to allow the protector to be readily applied to the seat of a stool. A retaining loop 10 is stitched or otherwise 75 secured to the upper strip 3 near the rear thereof as indicated at 11, and this retaining band 10 is adapted to pass under the cap 12 of the hopper 13 as illustrated clearly in Figs. 1 and 2. The retaining 80 loop 10 carries a plurality of snap eyes 14 which are adapted to engage a suitable snap hook carried by the face of the outer strip 3 near the rear end thereof so as to allow the retaining strap 10 to be adjusted and 85 detachably secured at its free end to the upper face of the outer strip 3 and efficiently hold the same in position.

90 It, of course, should be understood that other suitable fastening means such as buttons and the like may be employed if so desired without departing from the spirit of the invention.

95 It is preferable to make the sanitary slip out of fabric such as will absorb any moisture, although it is not necessary that this material be used as tough tissue paper or other suitable material of any nature may be employed without departing from the 100 spirit of the invention.

Having thus described the invention what is claimed as new, is:—

105 As a new article of manufacture, a stool slip comprising an upper strip having a centrally located aperture formed therein, a reinforcing band passing around the periphery of said aperture, a lower strip comprising a substantially U-shaped body provided with an outer and an inner edge securely fastened to the outer periphery of 110 said upper strip, a reinforcing band stitched around the entire adjoining edges of the

upper and lower strips, a reinforcing strip extending around the inner edge of said lower strip, said upper and lower strips adapted to straddle the front and side portions of a seat, and a retaining loop fixedly secured at one end to the rear of said upper strip and detachably secured at its opposite end to said upper strip and adapted to

pass under the cap of a hopper for firmly holding said slip upon a seat.

In testimony whereof I hereunto affix my signature in presence of two witnesses.

EMMA K. MUNCH.
